SWIVEL CHAIR

Frank B. Harman, Sturgis, Mich.

Application March 22, 1939, Serial No. 263,343

3 Claims. (Cl. 155—93)

This invention relates generally to swivel chairs and more particularly to a swivel chair having a supporting spindle with which cooperates a mechanism by which the height of the seat can be adjusted.

The object of this invention is to provide a swivel chair which may be manually adjusted to a proper elevation by a person sitting in the chair irrespective of the position of the seat portion relative to the base and which may be freely rotated without affecting the height of the seat.

In the accompanying drawing is an illustrative embodiment of this invention, wherein:

Figure 1 is an elevation of a swivel chair having the new supporting mechanism;

Figure 2 is an enlarged section taken on the line 2—2 of Fig. 1;

Figure 3 is a vertical section taken on the line 3—3 of Fig. 2; and

Figure 4 is a fragmentary section taken on the line 4—4 of Fig. 3.

A swivel chair following the design of this invention would include some suitable seat portion 10 to which may be joined a back 11. The seat portion may be of any of the customary styles or may be a simple support having neither arms nor back. The seat 10, whether of the tilting or non-tilting type, is supported on a spindle 12, which, in the case of the non-tilting type herein shown, may be rigidly connected to the seat through a spider 13. The spindle may be keyed to or integral with the spider.

The spindle 12 is preferably steel and has a threaded portion 14 through which extends a longitudinal groove 15. This spindle is journaled in bearings 16 and 17 which are mounted in a base frame 18.

The base frame may be of wood, metal or any other suitable material and is preferably high enough so that the entire threaded portion 14 of the spindle 12 can pass through the bearings 16 and 17.

Upon the spindle 12, at a point between the base and the seat is located a mechanism 20 which serves the two-fold purpose of maintaining the spindle 12 at a certain level in the base 18 and of permitting the level of the spindle in the base to be raised or lowered by a single manual control.

The mechanism 20 comprises a worm wheel 21 having internal threads 22 which cooperate with the threaded portion 14 of the spindle 12, a worm 23 which is meshed with the worm wheel 21, and a manually operable shaft 24 upon which is keyed by set screw 25 the hub of the worm 23.

A housing 26 completely encloses the mechanism 20.

The housing 26 is preferably made of two metal stampings 27 and 28 having upper and lower vertical bearings 29 and 30 respectively. The housing is carried by the worm wheel 21 and is maintained in a stable position on the worm wheel by having the spindle 12 extending through bearing 29 and having a hub 31 of the worm wheel 21 extending through the bearing 30. The housing is slidably keyed to the spindle 12 by a key 32 which is cut out of the bearing 29 and which engages the longitudinal groove 15 of the spindle 12.

Rotatably supported by the housing 26 at bearing points 33 and 34 is the shaft 24. The shaft is secured against endwise movement by the screw 25 and the bearing of the worm hub on the adjacent side wall of the housing and by the insertion of a spacer sleeve 35 between the bearing point 34 and the worm 23. On one end of the shaft is fixed a hand wheel 36 for manually rotating the shaft. The handle 36 is placed on an end of the shaft which is sufficiently extended so that the wheel may be conveniently operated by any person sitting in the chair.

The worm wheel 21 supports the spindle 12 in the base 18 by the abutment of the lower end of its hub on the bearing 16. The position of the worm wheel on the spindle determines the height of the seat. The worm wheel cannot turn on the spindle under the weight of the occupant of the chair because it is locked against such turning by the worm, and the housing in which the worm is journaled is locked against turning on the spindle by the key 32. The seat may be freely rotated relatively to the base without altering the elevation of the seat, since at such time the spindle, worm gear, worm and housing are all locked against relative rotation but rotate with the seat; the hub 31 of the worm wheel 21 sliding over the top face 37 of the bearing 16.

To operate the mechanism 20 in order to change the elevation of the seat 10, a person seated in the chair need only to reach beneath that portion of the seat where the handle 36 will always be found, turn the shaft 24 by means of handle 36 which will in turn rotate the worm 23 and thus the worm wheel 21. The rotation of the worm wheel will cause the spindle 12 which is keyed to the housing 26 and thereby indirectly to the shaft 24 to move up or down depending on which way shaft 24 is turned rather than rotate. This vertical movement will be relative to the mechanism 20 which continuously abuts

upon the base 18 and, therefore, will result in a change of the elevation of the seat portion 10. When elevating the spindle, the down thrust of the worm wheel 21 is opposed by the bearing 16. When lowering the spindle the up thrust of the worm wheel is opposed by the weight of the seat or the occupant of the seat acting on the worm wheel through the spindle, the worm wheel acting at such time merely as a regulator 10 of the down movement of the spindle. The gear ratio between the worm 23 and the worm wheel 21 will determine the effort and the speed with which any adjustment can be made. Other gearing arrangements than that described (e. g. two 15 bevel gears) may also serve in the mechanism.

Having the handle 36 keyed indirectly through the housing 26 to the spindle 12 makes possible the feature of having the handle always in the same position relative to the seat 10 irrespective 20 of the position of the seat with respect to the base.

I claim:

1. In a chair of the type described, the combination of a base structure having a vertical spindle guide, a seat, a vertical spindle at its upper 25 end secured to and supporting said seat, said spindle having a threaded portion slidably engaged with said spindle guide, a worm wheel having an internally threaded hub engaged with the threaded portion of said spindle and at its lower 30 end stepped on said spindle guide, a housing encircling said spindle and enclosing said worm wheel, means rendering said housing non-rotatable relatively to said spindle but permitting vertical travel of the latter through said housing, a 35 shaft journaled in opposite walls of said housing, a worm fast on said shaft engaged with said worm wheel, and a hand wheel on said shaft.

2. In a chair of the type described, the combination of a base structure having a vertical 40 spindle guide, a seat, a vertical spindle at its

upper end secured to and supporting said seat, said spindle having a threaded portion slidably engaged with said spindle guide and a longitudinal groove, a worm wheel having an internally threaded hub engaged with the threaded portion 5 of said spindle and at its lower end stepped on the upper end of said spindle guide, a housing encircling said spindle and enclosing said worm wheel, said housing having a key in sliding engagement with said longitudinal groove of the 10 spindle and a vertical bearing encircling said hub, a horizontal shaft journaled in opposite side walls of said housing, a worm fast on said shaft engaged with said worm wheel, and a hand wheel on one end of said shaft. 15

3. In a chair of the type described, the combination of a base structure having a vertical spindle guide, a seat, a vertical spindle at its upper end secured to and supporting said seat, said spindle having a threaded portion slidably 20 engaged with said spindle guide and a longitudinal groove, a worm wheel having an internally threaded hub engaged with the threaded portion of said spindle and at its lower end stepped on the upper end of said spindle guide, a housing encircling said spindle and enclosing said worm wheel, 25 said housing having a key in sliding engagement with said longitudinal groove of the spindle and upper and lower vertical bearings, said upper bearing encircling the spindle with its lower end bearing on the upper face of the worm wheel and said lower bearing encircling the hub of the worm wheel with its upper end bearing the lower face of the worm wheel, whereby said housing is locked 30 against vertical displacement relatively to the worm wheel, a horizontal shaft journaled in opposite side walls of said housing, a worm fast on said shaft engaged with said worm wheel, and a hand wheel on one end of said shaft. 35
